CLAIM

The ornamental design for safety goggles, as shown and described.

DESCRIPTION

FIG. 1 is a front view of safety goggles, showing our new design;

FIG. 2 is a rear view thereof;

FIG. 3 is a top view thereof;

FIG. 4 is a bottom view thereof;

FIG. 5 is a lateral view (right side) thereof;

(Continued)

FIG. 6 is a lateral view (left side) thereof; and,
FIG. 7 is a perspective view thereof.
